United States Patent Office

Des. 198,362
Patented June 9, 1964

198,362

DOOR PULL

Donald H. Munro, Pasadena, Calif., assignor to Parlyn,
Inc., Monterey Park, Calif., a corporation of California

Filed Jan. 26, 1962, Ser. No. 68,525

Term of patent 14 years

(Cl. D10—7)

Fig. 4

FIG. 1 is a front elevation of a door pull showing my new design;

FIG. 2 is a side elevation thereof, as seen from the right of FIG. 1;

FIG. 3 is a side elevation thereof, as seen from the left of FIG. 1;

FIG. 4 is an end elevation thereof.

I claim:

The ornamental design for a door pull, as shown.
